ROSWELL BURNS REID AND HARRY JACOB LEWELLEN, OF CONNELLSVILLE, PENNSYLVANIA, ASSIGNORS TO BOYTS, PORTER & CO., OF CONNELLSVILLE, PENNSYLVANIA.

STEAM CHEST FOR PUMPS.

Application filed December 2, 1919. Serial No. 341,978.

Our invention relates generally to steam chests and particularly to a chest adapted for use in conjunction with a pump, the purpose of our invention being the provision of a steam chest in which the oscillating valve for controlling the action of the usual slide and auxiliary valves is removably associated with the chest to permit of the reseating or substitution of the valve without necessitating the removal of the steam chest to a repair shop.

It is also a purpose of our invention to provide a steam chest in which the oscillating valve is seated and pressed by the operating fluid against the head instead of in the body of the steam chest, whereby it is only necessary to reface the valve and inner surface of the head to make a new and perfect seat for the valve.

20 We will describe one form of steam chest embodying our invention, and will then point out the novel features thereof in claims.

In the accompanying drawings:—

25 Figure 1 is a view, showing in end elevation one form of steam chest embodying our invention;

Figure 2 is a view, showing in front elevation the steam chest shown in Figure 1 with a portion of the chest head removed;

30 Figure 3 is a top plan view of Figure 2;

Figure 4 is a view, showing in elevation the inner side of the removable portion of the chest head;

Figure 5 is a central horizontal sectional view of Figure 4;

Figure 6 is a fragmentary vertical sectional view of Figure 4;

Figure 7 is a view, showing in side elevation, and partly in section, one form of valve embodying my invention adapted to be used in conjunction with the chest head shown in the preceding figures;

45 Figures 8 and 9 are views, showing in front and rear elevation, respectively, the valve shown in Figure 7;

Figure 10 is a diagrammatic view, showing the steam passages and ports and the manner in which they are controlled by the valve.

50 Fig. 11 is a perspective view, with parts disassembled, of the steam chest,

Fig. 12 is a cross section illustrating the relation of the steam chest to the engine cylinder,

Fig. 13 is a longitudinal section on the 55 line 13—13 of Fig. 12, and

Fig. 14 is a front elevation of the steam chest showing (in dotted lines) the positions of the steam ports when the oscillating valve handle is turned to the right. 60

Similar reference characters refer to similar parts in each of the several views.

Referring specifically to the drawings, and particularly to Figures 1, 2 and 3, B designates the body of the steam chest which 65 is of cylindrical formation and is provided at its opposite ends with annular flanges 15 to which head plates 15^a are adapted to be bolted for closing the ends of the body. The under side of the body B is formed 70 with a base plate 16 for the purpose of securing the steam chest as a unit in proper distributing position upon the steam cylinder C (Figs. 12 and 13). Inside of the steam chest is an auxiliary piston 33 which 75 has a recess 34 to receive the shank 35 of a slide or a D-valve 36. The auxiliary piston is adapted to reciprocate, and the slide valve controls the various steam passages shown in Fig. 13, of which 37 is the inlet, 38 the exhaust, 39 the port to the right end of cylinder C, and 40 the port to the left end. The auxiliary valve carries a rod 36^a which in practice may be used to reciprocate it by hand. This feature has 80 no bearing on the invention and therefore needs no elaboration. Formed at one side of the body B is a chest including a flanged section H formed 85 integral with the body B and a second section or head H' detachably associated with the section H. The section H is of cylindrical formation to provide a pocket 17 in which is adapted to work an oscillatory valve V, and, as shown in Figure 2, the inner wall of the pocket is formed axially thereof with an opening 17^a which is adapted to receive a projection 18 (Figure 7) formed on the valve to properly position the same within the pocket. As shown 90 in Figures 2 and 3, the outer end of the section H is flanged, as at 19, and provided with holes to receive bolts 20 (Figure 1) which extend through the flange 19 and through a similar flange 19^a formed on the confronting end of the removable head section H' for securing the two sections together to provide a housing for the valve 95

100

105

V. The construction of the section H' is clearly illustrated in Figures 4 and 5, wherein it will be seen that inside the flange 19^a, a circular boss 21 is formed, and extending radially on the outside of said head are thickened portions 22, 23 and 24 which are provided with ports 22^b, 23^a, and 24^a, respectively, that communicate with ports 22^b, 23^b, and 24^b, respectively, formed in the boss 21. As shown in Figure 5, the inner side of the boss 21 projects beyond the surface of the flange 19^a, and this projected portion is adapted to fit snugly within the pocket 17 of the section H. The head H' is bored axially and is provided at its outer side with an annular collar 21^a through which a shaft 25 for the valve V is adapted to extend. This collar is shown threaded for the purpose of receiving a stuffing box 21^c which is illustrated in Figures 11 and 12. The inner side of the boss 21 is provided with a pair of pins 26 and 26^a which are adapted to limit the movement of the valve V as will be described hereinafter.

As clearly shown in Figures 1 and 3, the upper side of the body B is formed with a pocket 27 to which a suitable form of lubricator (not shown) is adapted to be connected for effecting the lubrication of the auxiliary and slide valves contained within the body. As shown in Figure 2, the inner face of the pocket 17 is provided with a port 17^b through which steam from the body B is adapted to enter the pocket, and steam from the pocket 17 is adapted to be returned to the body B through the ports in the section H' and other ports 28 and 28^a in the section H.

The valve V is of the oscillatory type, details of which are shown in Figs. 7, 8 and 9. An arcuate steam inlet port 31 occupies approximately the lower half of the valve (Fig. 9) and extends completely through (Fig. 7) in order to transfer steam from the pocket 17 to one or the other of the ports 22^b or 23^b (Figs. 4 and 14) with which said inlet port happens to be in registration.

A depression or cavity 32^a on the front face (Figs. 7 and 8) of the valve furnishes a space adjacent to the confronting face of the pocket 17 which is filled with live steam while the pump is in operation. An exhaust passage 32 is formed on the reverse face of the valve, occupying approximately the upper half as shown in Figs. 8, 9 and 14. In this respect the exhaust port is like the inlet port 31, the passage 32, however, does not extend through (Figs. 7 and 12). The shoulders 31^a, 31^b (Fig. 9) formed by the inlet port 31 furnish abutments which strike against the pins 26 and 26^a on the head H' (Fig. 4) to limit the oscillation of the valve.

The operation of the mechanism is as follows: Steam is initially admitted at the

inlet 37 (Fig. 13) whence it occupies the chamber 41 of the steam chest. The port 17^b (Figs. 2, 11 and 12) has been described as affording a passage between the chest B and the valve pocket 17. Were it not for an annular reduction 42 on the auxiliary piston 33 this passage would be cut off, but said reduction is provided for the express purpose of maintaining a continuous steam-communication through 17^b between the interior 41 of the steam chest B and pocket 17.

Consider the oscillatory valve V as having been turned toward the left as in Figs. 10 and 14. The inlet port 31 will establish communication between the port 22^b and the interior of the pocket 17 so that steam flows from the chamber 41 (Fig. 13), port 17^b into pocket 17, port 31, ports 22^b and 22^a to the passage 28^a which leads to the right end of the chest B. The auxiliary piston 33 (Fig. 13) will naturally be forced to the left, carrying the D-valve 36 with it. Steam which we now consider as entering the port 40, will be cut off and the port 39 will be opened.

Exhaust steam from the left end of the steam chest will be forced through the left passage 28 (Fig. 14), ports 23^a and 23^b, arcuate passage 32 and out at the central exhaust ports 24^b, 24^a and 29. A reversal of the oscillatory valve produces a reversal of the passage of live and exhaust steam in the various ports.

Should the valve V for any reason become ineffective to properly control the passages and ports in the manner just described, it is obvious that a new valve may be substituted or the present one repaired by removing the section H' of the chest head, thus permitting the ready removal of the valve and shaft 25. This mounting of the valve so as to permit its removability from the steam chest is one of the important objects of our invention, as in steam chests of the ordinary construction, the valve is so associated with the chest as to necessitate the removal of the entire steam chest in order that the valve may be repaired or a new one substituted. It is manifest that with the valve of our construction, associated with the steam chest in the manner described, the necessity of removing the entire steam chest is eliminated, and the valve can be repaired or a new one substituted without in any way disturbing the mounting of the steam chest.

Although we have herein shown and described only one form of steam chest embodying our invention, it is to be understood that various changes and modifications may be resorted to without departing from the spirit of the invention and the spirit and scope of the appended claims.

Having thus described our invention, we claim:

1. A steam chest comprising a body hav-

ing a steam chamber provided with a steam inlet and a port furnishing an outlet for steam from the chamber, a circular valve pocket formed in an exposed face of the body communicating with said chamber to receive live steam through said steam port, an exhaust passage opening on said exposed face and being adapted to communicate with an exhaust port and a pair of intake passages also opening on said exposed face; a head providing a closure for said pocket having ports furnishing communication between said respective passages and the interior of said valve pocket, and a valve operable in said pocket having an inlet port extending through from side to side to furnish communication between said steam port and one of the intake passages in the head and having an exhaust passage formed in the face confronting the head to furnish communication between the other intake passage and the exhaust passage.

2. A steam chest comprising a body having a steam chamber provided with a steam inlet, a circular valve pocket formed in an exposed face of the body communicating with said chamber through a steam port, a substantially upright exhaust passage opening on said exposed face and being adapted to communicate with an exhaust port and with a pair of intake passages situated laterally of said exhaust passage, said pair of passages also opening on said exposed face; a head providing a closure for said pocket having an independent port for each of three passages furnishing communication between said respective passages and the interior of said valve pocket, and a valve operable in said pocket having an inlet port

extending through from side to side to furnish communication between said steam port and one of the intake passages in the head and having an exhaust passage formed in the face confronting the head to furnish communication between the other intake passage and the exhaust passage, said valve having a depression in the face confronting the steam port to receive steam pressure to forcibly seat the valve against the inside of the head.

3. A steam chest comprising a body having a steam chamber provided with a steam inlet, a flange formed upon the body having a circular valve pocket, there being a steam port providing perpetual communication between the steam chamber and the pocket, an exhaust passage in the body opening upon the front face of the flange, a pair of intake passages in the body each opening upon the front face of the flange at places opposite each other, a head to fit upon the flange and cover the valve pocket, said head having three ports each respectively registering with one of said passages, and a valve operable in said pocket having a depression in the face confronting the steam port to receive the direct impact of the steam and steam chamber-pressure to thereby be forcibly seated against the inside of the valve head, said valve having an inlet port extending therethrough to furnish steam to one of said intake passages when the valve is properly turned and also having an exhaust passage formed in one face to provide communication between the other intake passage and the exhaust passage in the body.

ROSWELL BURNS REID.

HARRY JACOB LEWELLEN.
